UNITED STATES PATENT OFFICE.

JESSE HAM, OF EMERY MILLS, MAINE.

INSECT-DESTROYER.

SPECIFICATION forming part of Letters Patent No. 750,030, dated January 19, 1904.

Application filed April 3, 1903. Serial No. 150,903. (No model.)

To all whom it may concern:

Be it known that I, JESSE HAM, a citizen of the United States, residing at Emery Mills, in the county of York and State of Maine, have 5 invented certain new and useful Improvements in Insect-Destroyers, of which the following is a specification.

My invention relates to devices for killing flies and other insects, and has for its object 10 to provide a device of the character described in which a wire screen forming the striking-surface is mounted on the end of a spring-actuated plunger, so that the operator stands opposite the fly and takes aim instead of, as in 15 the devices in common use, swinging a screen-surface through the air, thereby not insuring a good aim and at the same time risking frightening the insect.

By providing a spring for receiving the 20 screen-surface said surface will strike the wall or other surface flatly even though the plunger be held obliquely to the perpendicular of said surface.

The construction and operation of my invention will fully appear hereinafter and by 25 reference to the accompanying drawings, in which—

Figure 1 is a side view, partly in section, of 30 my invention; and Fig. 2, an end view of the plunger.

Referring to the drawings, in which similar reference characters indicate corresponding parts in both views, A represents the handle of my device having a longitudinal bore B, in 35 which is mounted plunger C, having at one end a handle D and at the other an evolute spring E. The end of spring E is secured, as shown at F, to form a ring F', on which is secured a strip of wire-gauze fabric G to form 40 the striking-surface. H represents a retractile coil-spring secured at one end to the han-

dle D and at the other to the end of bore B to actuate said plunger C.

The operation of my invention will be readily understood to be as follows: The handle 45 A is grasped with one hand by the operator, while with the other the plunger C is drawn back. When the handle D is released, the spring H impels the plunger C forward, and the wire surface G strikes the wall. As stated 50 above, the spring E permits the plunger being held obliquely to the surface of the wall, the surface G nevertheless striking the wall flat.

Having thus described my invention, what 55 I claim is—

1. In an insect-destroyer, a plunger, an evolute spring on the end of said plunger ending in a ring, a strip of wire-gauze fabric secured to said ring, and means to actuate the plunger, 60 substantially as shown and described.

2. In an insect-destroyer, a plunger, an evolute spring on the end of said plunger ending in a ring, a strip of wire-gauze fabric secured to said ring, and a retractile coil-spring to actuate said plunger, substantially as shown and 65 described.

3. In an insect-destroyer, a handle having a longitudinal bore, a plunger mounted in said bore, a retractile coil-spring wound around 70 said plunger having one end secured to the end of said plunger and the other end secured in said bore, an evolute spring on the free end of said plunger ending in a ring, and a strip of wire-gauze fabric secured to said ring, substantially as shown and described. 75

In testimony whereof I hereto affix my signature in the presence of two witnesses.

JESSE HAM.
